Primary Examiner — John A Voytek*(74) Attorney, Agent, or Firm* — Cohen IP Law Group, PC; Michael N. Cohen(57) **CLAIM**

I claim the ornamental design for the swimming pool skimmer screen, as shown and described.

DESCRIPTION

FIG. 1 is a top perspective view of the swimming pool skimmer screen;

FIG. 2 is a top view of the swimming pool skimmer screen; FIG. 3 is a bottom view of the swimming pool skimmer screen; and,

FIG. 4 is a side view of the swimming pool skimmer screen. In the drawings, the broken lines depict environment and form no part of the claim.
